H. A. Seymour

UNITED STATES PATENT OFFICE.

SIDNEY H. SHORT, OF CLEVELAND, OHIO, ASSIGNOR TO THE SHORT ELECTRIC RAILWAY COMPANY, OF SAME PLACE.

MULTIPLE-ARC RAILWAY SYSTEM.

SPECIFICATION forming part of Letters Patent No. 473,361, dated April 19, 1892.

Application filed January 8, 1890. Serial No. 336,280. (No model.)

To all whom it may concern:

Be it known that I, SIDNEY H. SHORT, of Cleveland, in the county of Cuyahoga and State of Ohio, have invented certain new and useful Improvements in Systems of Distribution for Electric Railroads; and I do hereby declare the following to be a full, clear, and exact description of the invention, such as will enable others skilled in the art to which it applies to make and use the same.

My invention relates to an improved system of electric distribution for electric railroads.

The object of the invention is to provide a series of independent blocks or sections of conductor, each independently connected with the same or different generators, and automatic cut-out devices combined with each block or section, whereby an abnormal amount of current flowing through the conductor leading to any one of said sections, due to accidental or malicious short-circuiting of the conductors or other cause, will operate to automatically cut such section out of operation without interfering with the flow of current in any remaining sections.

With this end in view the invention consists in certain features of construction and combinations of parts, as will hereinafter be described, and pointed out in the claims.

The accompanying drawing is a diagrammatic representation of one embodiment of my invention.

A represents any suitable dynamo-electric machine, its negative terminal or binding-post being indicated by A' and its positive binding-post by A². The trolley lines or conductors B B' are each subdivided into any desired number of insulated sections, which are preferably arranged so that the breaks in one conductor will alternate with those of the other. Each one of the several sections C of conductor B is connected with the positive binding-post A² by an independent conductor D, while each one of the sections C' of the conductor B' is connected with the negative binding-post A' by an independent conductor E. Within each one of the conductors E is included a safety-fuse F, which is so constructed that should an abnormal amount of current be diverted through it by reason of a

short circuit or other cause the fuse will be blown out, and thus open-circuit that particular section and render it inoperative, but without interfering with the flow of current to the other sections of the line.

In the drawing I have represented a number of motors G, G', G², G³, and G⁴ receiving current from different portions of the sectional trolley-line. For the sake of illustration we will suppose that the line is short-circuited, so that an abnormal amount of current tends to flow through the circuit in which the motor G' is included. Any such abnormal flow of current will instantly blow out the fuse F in the conductor connected with the section of the trolley-line from which motor G is being supplied with current and instantly render such section inoperative, and yet in no wise interfere with the other sections of the line. The current flows from the generator by a conductor to one of the sections of the trolley-line, and from thence to the trolley and through the motor, and from thence back by another trolley, to a section of the other trolley-line and from thence back to the generator. Hence it will be observed that I provide separate and independent trolley-line sections and furnish each section with separate and independent conductors leading to the generator.

Instead of using safety-fuses I may use electro-magnetic cut-outs so constructed that on the flow of an abnormal amount of current through any of the circuits E an electro-magnet will automatically open-circuit such conductor and render it and the trolley-section connected therewith inoperative.

Having fully described my invention, what I claim as new, and desire to secure by Letters Patent, is—

1. The combination, with a generator and two sectional trolley lines or conductors, of a series of feed-wires extending from one pole of the generator to and connected with the respective sections of one trolley-line, and an automatic cut-out included in each one of said feed-wires at a point near the generator, and a series of feed-wires extending from the other pole of the generator to and connected with the respective sections of the other trolley-line, substantially as set forth.

2. The combination, with a generator, of two trolley lines or conductors, each conductor being composed of a series of insulated sections, the joints of the several sections of one trolley line or conductor alternating with the joints of the sections of the other trolley line or conductor, feed-wires connecting one pole of the generator with the respective sections of one trolley line or conductor, an automatic cut-out device in the circuit of each feed-wire, and a series of wires connecting the sections

of the other trolley wire or conductor with the other pole of the generator, substantially as set forth.

In testimony whereof I have signed this 15 specification in the presence of two subscribing witnesses.

SIDNEY H. SHORT.
